INVENTOR

UNITED STATES PATENT OFFICE

REYBURN T. CHASE, OF CAMDEN, NEW JERSEY

CAN OPENER

Application filed July 8, 1927. Serial No. 204,379.

My invention relates to that type of can opener in which the top of the can is cut out by a sheer blade set at an oblique angle to the top, and which is held down and pulled along 5 by a toothed wheel rolling against the rim of the can.

The object of my invention is to provide a can opener that will be easy to make, easy to use, and that will cut the entire top out of 10 the can so that contents of a solid nature will empty out in bulk; and that will leave the rim on the can so that contents of a liquid nature will not spill while the can is being opened; and that will leave no jagged or 15 sharp edges to cut the hands. The rim being left on the can with the top cut out smoothly and close to the rim leaves the can so that it may be used for other purposes after the contents are removed. This opener can be made 20 with as few as three pieces. Turning the key in one direction will start and continue the cut, and turning it in the other direction will open it for removal from the can. If desired, the blade may be made adjustable, or may be 25 fastened to the frame by screws or clips so that it may be replaced by longer or shorter blades to cut cans with deeper or shallower tops.

I attain these objects by the means illustrated in the accompanying drawings, in which—

Fig. 1 is front view of the opener, mounted on a can in the cutting position, with a part of the can broken away to allow the shearing blade to be seen.

Fig. 2 is a view of the key side of the opener.

Fig. 3 is a view of the shearing side of the opener.

In all the figures, the numeral 1 represents the frame, one portion of which is formed 40 into the shearing blade 2, and other portions are formed into the guides 4 and 5 which hold the opener in its proper position on the can, and another portion 6 is bent to form a finger, against which the cam 7, which is attached

45 to the key 8, bears and forces the shaft 10 up through the slot 3 when the key 8 is turned in a right hand or clock-wise direction. This movement forces the toothed wheel 9 which is attached to the shaft 10, up against the lower 50 edge of the rim of the can, and forces the

pointed corner 11 of shear blade 2 down against the top of the can, and a further movement of the key and attached parts causes the point to pierce the top, and then draw the blade down to the shearing position, when the 55 shaft reaches the upper end of the slot and the opener is drawn along the rim thus shearing the top close to the rim. To remove the opener from the can, the key is turned in the opposite direction to that in which the cutting 60 was done, and this causes the shaft 10 to recede down through the slot 3, thus releasing the opener so that it may be lifted off the can.

I claim:

1. In a can opener, the combination of a 65 frame; a traction wheel so mounted that it may move across the body of the frame to engage or disengage the rim of the can; means for turning the traction wheel; a shearing blade mounted on the frame as a part thereof, 70 and having a penetrating portion and a diagonal shearing edge, and means for forcing the traction wheel toward the shearing blade.

2. In a can opener, the combination of a 75 frame having a pointed shear blade attached thereto and as a part thereof, and so made as to be rigid against the strains of cutting but resilient to allow the opener to pass over any enlargement of the wall of the can; a traction wheel arranged to engage the lower edge of 80 the bead of a can; means for turning the traction wheel; means for allowing the traction wheel to approach or recede from the shear blade along the body of the frame; and means for forcing the traction wheel toward the 85 shear blade.

3. In a can opener, the combination of a frame having a shear blade attached thereto and as a part thereof; means for moving the frame normal to the part to be cut for the 90 purpose of puncturing it; and means for moving the frame along the rim of the can for the purpose of shearing the adjacent part from the rim.

4. In a can opener, the combination of a 95 frame having a shear blade as a part thereof; a traction wheel arranged to engage the under side of the rim of a can, and so mounted on the frame that it can move toward or away from the shear blade; means for turning the 100

traction wheel; means for forcing the traction wheel toward the shear blade so that on the first movement of the traction wheel the blade will be forced through the metal of the can; and a stop to limit the linear movement of the wheel so that as the rotation of the wheel continues a shear cut is made.

5 5. In a can opener of the type described, the combination of a slotted frame plate having 10 a laterally projecting arm adapted to ride on the bead of a can and a cutter blade rigid with, and disposed opposite the inner side of said frame plate, an operating handle having a shank extending through the slot of said 15 frame plate, a feed wheel fast on the inner end of said handle shank, and cooperating means on said frame plate and handle operative to advance said feed wheel into gripping engagement with said bead when said handle 20 is turned in one direction.

6 6. In a can opener of the type described, the combination of a frame plate formed with an inclined slot, an integral laterally projecting arm on one edge thereof adapted to 25 ride on the bead of a can, and an integral inwardly extending cutter blade on another edge thereof lying opposite and substantially parallel with the inner side of said frame plate and formed with a lower cutting edge 30 having a piercing point, an operating handle having a shank extending through the slot of said frame plate, a toothed feed wheel fast on the inner end of said handle shank, a lug on 35 said frame plate, and a cam fast with said handle cooperating with said lug to advance said feed wheel into gripping engagement with said bead when said handle is turned in one direction.
